UNITED STATES PATENT OFFICE.

JOHN FOLK, OF NEW YORK, N. Y.

PROCESS OF PRINTING ON TEXTILES, FABRICS, AND THE LIKE.

Application filed January 22, 1925. Serial No. 3,993.

To all whom it may concern:

Be it known that I, JOHN FOLK, a citizen of Hungary, and resident of the borough of Manhattan, city of New York, in the 5 county of New York and State of New York, have invented certain new and useful Improvements in a Process of Printing on Textiles, Fabrics, and the like, of which the following is a specification.

10 This invention relates to the process of printing on textiles, fabrics and the like.

The object of the invention is to transfer designs made on a base like paper, to textiles, woven fabrics and the like. The 15 second object of the invention is to provide steps by means of which designs are printed on finished or semi finished articles of manufacture like dresses, waists and the like, in any stage of their manufacture. The 20 third object of the invention is to reduce the cost of decorating textiles, fabrics and the like to a minimum.

The organization of the invention comprises the preparation of a base, like paper 25 with one face thereof waterproofed, printing with dies on its opposite face, superposing a textile or fabric to be printed upon on the printing of the base, then locating a damp rag upon the top face of the textile or fabric, and then ironing the top face of the latter preferably with a smoothing iron. The ironing generates steam which can not escape through the water proofed face of the base or paper and enhances the penetration 30 of the dyes into and about the fibers of the said textile or fabric.

The accompanying drawing represents the instrumentalities, by means of which the steps of the printing or reprinting process 35 is carried out.

In said drawings 10 represents a prepared base with a design or configuration 40 printed thereon. A textile or fabric 12 to be printed upon is located upon the top face 45 of the base 10. A damp rag 13 is shown upon the textile 12, and 14 indicates a hot smoothing iron upon the said damp rag.

To carry out the steps of the process the base 10, which is preferably paper, water 50 proofed on its rear or bottom face has printed on its top face the design or configuration 11 to be transmitted to the textile or fabric 12. The design is printed on the top face of the paper 10 opposite to its 55 water proofed surface with dyes, by means

of well known printing processes, using stencils rollers and the like. The dyes when being used preferably have the consistency of paste, and the paper after being printed is kept dry. The paper or base 10 with the 60 design printed thereon is located upon a flat surface, preferably a flat board with its water proofed surface bearing upon said flat surface or board, the surface of the base 10 with the design being on the top. Next the 65 textile or fabric 12 to be printed upon is smoothly located upon the design 11 of the base 10. The damp rag 13 which may be cotton, linen or other suitable fabric is next placed upon the textile 12, and the hot 70 smoothing iron 14 is moved over and pressed upon said rag 13 in a manner similar to ordinary ironing, until the rag is dry.

The heat of the iron will generate steam, which coacts with the dye on the base 10 75 and the textile, which provides the after steaming step in the ordinary textile printing process, to set the dyes into the texture of the textile, penetrating and covering the fibers thereof. The rag 13 and paper base 80 10 are then removed from the textile or fabric 12 and the design will have been printed thereon.

The object of the water proofing of one face of the base or paper 10 is to maintain 85 the printed dye adjacent to its outer face, preventing its deep entrance into the base or paper, and thereby maintaining the dyes in proper position to penetrate the textile or fabric printed upon. The water proofed 90 side of the base or paper 10 constitutes a barrier to the steam generated and maintains it in the textile or fabric printed upon. Any shade of textile or fabric can be printed upon with the steps of this process, from 95 white to the darkest black. For dark shades of material the dyes, generally called printing paste is prepared by the known discharge printing methods.

The textile or fabric to be printed upon 100 may be of any quality, for instance it may be cotton, silk, artificial silk, wool or mixed goods, which can be pressed. Any number of colors can be used in the design to be reprinted. The finished reprinted 105 material has the appearance of ordinary textile prints. The material, textile or fabric after reprinting is delivered with its original texture, construction, surface appearance and softness.

The base or paper can be stored for any length of time if kept dry, and can be produced in sheets or rolls.

Various modifications may be made in the process and the present exemplification is to be taken as illustrative and not limitative thereof.

Having described my invention what I desire to secure by Letters Patent and claim 10 is:

1. The process of printing on textiles, fabrics and the like, consisting in printing a design, legend or configuration upon a base, locating the textile or fabric upon the printed face of the base and bearing against its design, locating a damp sheet of material upon said textile, fabric and the like, pressing the three elements together and simultaneously heating them.
2. The process of printing on textiles, fabrics and the like consisting in printing a design, legend or configuration upon a base of paper, said base waterproofed on its face opposite to its printed face, locating the textile or fabric upon the printed face of the base of paper, locating a damp sheet of material upon said textile, fabric and the like, and bearing with pressure and heat upon said sheet of material.
3. The process of printing on textiles, fabrics and the like consisting in printing with dyes a design, legend or configuration upon a base of paper, said base having pre-

viously been waterproofed on its face opposite to its printed face, locating the textile or fabric upon the printed face of the base of paper, locating a damp rag upon said textile, fabric or the like and ironing with heat the top face of said rag, thereby generating steam, to enhance the penetration of the dyes on the base of paper into and about the fibers of the textile and fabric, and also preventing the escape of steam generated through the waterproof face of the base of paper.

4. The process of printing on textiles, fabrics and the like, consisting in providing a base waterproofed on one face thereof, printing with dyes on the other face of said base, a design, legend or configuration, locating the textile or fabric upon the printed face of the base, locating a damp sheet of material upon said textile, fabric and the like, pressing the three elements together and simultaneously heating them, thereby generating steam to enhance the penetration of the dyes of the base into and about the fibres of the textiles, fabric and the like and simultaneously preventing the escape of the steam generated, through the base by means of the waterproofed face thereof.

Signed at the borough of Manhattan, city of New York, in the county of New York and State of New York this 17th day of January A. D. 1925.

JOHN FOLK.
